United States Patent

Des. 238,530

Patented Jan. 27, 1976

238,530

TOILET TISSUE HOLDER

George D. Read, Glendora, Lawrence Glen McCain,
Beverly Hills, and Edward William Scott, Culver City,
Calif., assignors to Ajax Hardware Corporation, City of Industry, Calif.

Filed Oct. 15, 1974, Ser. No. 514,824

Term of patent 14 years

Int. Cl. D23—02

U.S. Cl. D6—97

Fig. 1.

Fig. 2.

Fig. 3.

Fig. 4.

Fig. 5.

Fig. 6.

FIG. 1 is a front elevational view of a toilet tissue holder showing our new design;

FIG. 2 is a top plan view thereof;

FIG. 3 is a bottom plan view thereof;

FIG. 4 is a rear elevational view thereof;

FIG. 5 is a side elevational view thereof; and

FIG. 6 is a sectional view taken along line 6-6 of FIG. 1.

We claim:

The ornamental design for a toilet tissue holder, as shown.
